UNITED STATES PATENT OFFICE.

JOHN ISAAC MOSS, OF ABBOTSFORD, VICTORIA, AUSTRALIA, ASSIGNOR OF
ONE-HALF TO WILLIAM DAVID BEAZLEY, OF ABBOTSFORD, AUSTRALIA.

SELF-LOCKING WINDOW-FASTENER.

No. 852,517.

Specification of Letters Patent.

Patented May 7, 1907.

Application filed January 2, 1907. Serial No. 350,849.

To all whom it may concern:

Be it known that I, JOHN ISAAC Moss, a subject of the King of Great Britain, residing at 196 Vere street, Abbotsford, in the State 5 of Victoria, Australia, have invented certain new and useful Improvements in Self-Locking Window-Fasteners; and I do declare the following to be a full, clear, and exact description of the invention, such as will enable 10 others skilled in the art to which it appertains to make and use the same.

My invention relates to an improved window lock or catch and has been designed mainly for use in connection with railway 15 and tramway cars and the like, in which the windows when raised to the desired height are required to be held in that position.

By my invention the use of springs is rendered unnecessary the mechanism of the lock 20 being worked by gravity—the lock is simple in construction and not liable to get out of working order with the continual jolting of the car, and it is easy to operate which is of 25 advantage to women and children desirous of opening or closing the windows of the car.

The invention will be hereinafter fully described and particularly set forth in the claim.

In the accompanying drawings—Figure 1 30 is a side elevation showing my lock attached to a window and in engagement with a rack. Fig. 2 is a side view partly in section showing the position of the dog or catch when the same is out of engagement with the rack. 35 Fig. 3 is a front elevation of my lock, while— Fig. 4 is a plan view of the catch or dog.

I provide a metal casing which preferably 40 consists of a front piece A having a slot A' cut therein; projecting from the front piece are two flat cheek pieces B and B' one on either side of the slot A'—between the two cheek pieces the catch or dog C is eccentrically hung on a pin D. In its normal position the front of the catch or dog extends through 45 the slot in the front piece and is shaped as shown at C'; the catch or dog is provided at its rear end with a lifting thumb piece or finger plate E which extends a short distance on both sides of the catch or dog forming flanges

H and H', the flanges rest on top of the 50 cheek pieces B and B' which prevents the front C' of the dog from rising above the position shown in Fig. 1. The casing before mentioned is provided with extending lugs J which have perforations K through which 55 screws L are passed to secure the lock to the window M. N is a rack which may have any number of suitable teeth—when the window M is being raised the front C' of the catch or dog on coming into contact with a tooth of 60 the rack is moved to the position shown in Fig. 2; the catch will pass over the tooth and be brought again to the position shown in Fig. 1 by reason of the weight of the back 65 part of the catch.

When it is desired to lower the window the catch or dog is released from engagement with the rack by raising the thumb piece E, the front C' will then be in the position shown in Fig. 2 and the window may be lowered any desired distance—the thumb piece 70 is then released and the catch or dog by engagement with the rack will hold the window in its new position.

Having thus described my invention, what 75 I claim and desire to secure by Letters Patent is—

An improved window fastener comprising a casing provided with a front opening and rearwardly extended cheek plates, a dog eccentrically pivoted between said cheek plates and provided with a nose adapted to engage a rack, said dog being also provided with a finger piece or extension, said finger piece or extension being provided with lateral flanges 80 and so weighted as to normally tend to hold the nose of said dog projected through the front opening of said casing, the pivotal movement of said dog being limited by said flanges 85 and engaging said cheek plates. 90

In testimony whereof I have signed my name to this specification in the presence of two subscribing witnesses.

JOHN ISAAC MOSS.
